COMBINED CONTROL FOR RADIO RECEIVERS

Pierre Lebreton, Paris, France

Application April 10, 1951, Serial No. 220,157
In France April 19, 1950

3 Claims. (Cl. 74—10.7)

1

This invention relates to the means used for controlling the operation of radio-receivers in general and more particularly to a novel arrangement whereby two control mechanisms of a radio-receiver can be actuated simultaneously without resorting to any elaborate construction.

It is known that, as a rule, in every radio-receiver there are a plurality of wavebands and a continuously-variable element consisting of a capacitor or self-induction by means of which the precise wavelength of the desired broadcasting station can be selected in each band.

Thus, the user is generally confronted with the handling of two control buttons, the one for selecting the desired waveband, and the other for adjusting the variable element to the exact wavelength.

One drawback offered by these separate controls is that the user has to actuate two buttons separately, and another is that the external aspect of the receiver is unduly complicated by this conventional arrangement.

Of course, various devices have been devised for operatively connecting both controls, but their common drawback is their extreme intricacy.

It is the chief object of the present invention to provide a novel device permitting the combination into a single control button of both controls as specified hereinabove or, more generally, the control of the member which produces the continuous variation of the wavelength, and that of another member adapted to change the waveband or, if preferred, the tone control, etc.

In order to afford a clearer understanding of the invention the latter will be described hereinafter with reference to the affixed drawing illustrating diagrammatically by way of example a practical embodiment of the combined control for radio-receiver.

A lever 1 is pivotally mounted at one end on a fixed pivot pin 2 and formed with a slide 3 engaged by a pin 23 fixed on one end of a crank 4 the opposite end of which is fast with a shaft 5. This shaft is rotatably mounted in a fixed bearing. By displacing the lever 1 in the direction indicated by the arrow F or in the opposite direction the shaft 5 can be rotated through a certain angle through the medium of the crank 4 having its pin 23 slidably mounted in the slide 3. The shaft 5 may be used for rotatably driving the waveband changing device or member or any other desired device.

Besides, the lever 1 is formed with or carries in the vicinity of its centre a pair of bearings

6, 7 in which a shaft 8 is rotatably mounted. A groove pulley 9 is keyed on this shaft and therefore driven for rotation thereby in the bearings 6, 7. On the other hand a twin-groove pulley 10 is mounted for loose rotation on shaft 2.

The shaft through which the member adapted to effect the continuous variation in wavelength has keyed thereon a drum 11 formed with a peripheral groove engaged by a wire 12. One end of wire 12 is anchored to the drum at 13. Wire 12 is passed over one portion of the drum periphery, over pulleys 14, 15, 16, in one groove of pulley 10, over pulley 17; then the wire is wound a few turns round the control pulley 9, passed over pulley 18, in the other groove of pulley 10 and its other end is finally anchored through the intermediary of a tension spring 19 to the drum 11.

It will be noted that pulleys 17 and 18 are both mounted for loose rotation on small pins secured on a cross-member 20 fixed with the level 1. It is obvious that by rotating the shaft 8 by means of a control button the drum and therefore the variable device will be rotatably driven.

25 A slider 21 fast with the wire is adapted to move to and fro along a guide bar 22 and to be fitted with an index of any desired type.

With the control described the user, by gripping the lever through its shaft 8 and pivotally moving it about its fixed pin 2, may select the desired waveband of the receiver, and by rotating the shaft 8 about its axis, the user may also control the member which provides the continuous wavelength variation.

35 A control button 24 may be fitted to the outer end of shaft 8 and act as a means for gripping the shaft and applying thereto either an angular displacement in the plane of the figure or a rotational movement in either directions, both operations occurring either in succession and, if desired, simultaneously without releasing the button or actuating another control.

40 Of course, the drawing is merely a diagrammatical example for explaining the construction and operation of the combined control. It will be understood however that the lever may be displaced angularly in a plane other than that in which the drum 11 and pulleys 11, 14, 15, 16 rotate, without interfering with the operation 45 of the device.

Similarly, various modifications may be brought to the arrangement of the various guide pulleys, according to the type of receiver to which this control is fitted.

55 Furthermore, the position of slide 3 in relation

to pulleys 17 and 18 may be modified to suit any constructional requirements. Of course, these and other modifications may be made without departing from the spirit and scope of the invention.

What I claim is:

1. Combined control for switching the tuning inductances and actuating variable condenser of a radio receiver consisting of a lever fulcrumed at one end about a pivot pin, a longitudinal slot formed in said lever, another lever fulcrumed at one end about another pivot pin and formed at its free end with a crankpin slidably engaged in said slot, said other pivot pin being operatively connected with the tuning inductances of the 15 radio receiver, bearing means on said slotted lever, a spindle rotatably mounted in said bearing means, a control button arranged for rotating said spindle and simultaneously move said first lever angularly about its fulcrum, a grooved pulley 20 keyed on said spindle, twin-grooved pulley loosely mounted on the pivot pin of said first lever, a variable condenser control drum and a motion-transmitting wire having both ends anchored to said drum, a plurality of intermediate grooved 25 pulleys, said wire being wound round said pulley, twin-grooved pulley and intermediate grooved pulleys.

2. Combined control for radio receiver according to claim 1, comprising a slider fixed to said wire, an index on said slider, a rectilinear dial co-operating with said index, and two intermediate pulleys disposed at either end of said dial and round which said wire is passed.

3. Combined control for radio receiver according to claim 1, comprising a pair of loose pulleys mounted on said first lever on either side of said grooved pulley keyed on said spindle, said wire passing over said loose pulleys before and after forming a few turns round said grooved pulley on said spindle.
